UNITED STATES PATENT OFFICE.

MICHAEL G. SWARTWOOD, OF MANCHESTER, AND VERNON SWARTWOOD, OF CLAY CENTER, KANSAS.

FILTERING DEVICE.

1,113,066.

Specification of Letters Patent.

Patented Oct. 6, 1914.

Application filed December 29, 1913. Serial No. 809,360.

To all whom it may concern:

Be it known that we, MICHAEL G. SWARTWOOD and VERNON SWARTWOOD, citizens of the United States, residing at Manchester and Clay Center, respectively, in the counties of Dickinson and Clay and State of Kansas, have invented certain new and useful Improvements in Filtering Devices, of which the following is a specification, reference being had to the accompanying drawings.

This invention relates to new and useful improvements in filtering devices and our object is to provide an improved device of this character which is so constructed as to break the current of water as the same tends to pass therethrough, whereby said current may flow at a moderate rate of speed to permit heavy substances or sediment to settle at the bottom of the filter, where it may be readily drawn off.

A further object of the invention resides in providing a filter which is quickly and readily cleaned and one which may be used to operate on a small or large scale, such as domestic supplies and supplies for entire communities.

Still another object of the invention resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a vertical section through a device constructed in accordance with our invention. Fig. 2 is a horizontal section as seen on line 2—2, of Fig. 1. Fig. 3 is a similar view as seen on line 3—3, Fig. 1. Fig. 4 is a plan view of the inner filtering casing removed. Fig. 5 is a side elevation of the attachment applied to the inlet pipe. Fig. 6 is a horizontal section as seen on line 6—6, Fig. 1. Fig. 7 is an enlarged detail section through the lower end of the filtering casing, showing its supporting connection with the supporting flange on the main casing. Fig. 8 is a horizontal section as seen on line 8—8, Fig. 1;

and Fig. 9 is a plan view of one of the baffle plates used in connection with the device.

In describing our invention, we shall refer to the drawings in which similar reference characters designate corresponding parts throughout the several views and, in which—

1 indicates a main casing or housing, which has the bottom 2 thereof inclined somewhat toward one side of the same. Leading to and communicating with the interior of the casing or housing, at a point just above the uppermost point of the bottom, is an inlet pipe 3 which extends vertically upward along one side of the casing to a point above the upper edge thereof. Leading to and communicating with the casing or housing, immediately adjacent the top thereof, and on the side opposite that to which the inlet pipe leads, is an outlet pipe 4, which extends downwardly from the point of introduction into the housing and leads further to any desired point.

Adapted to be mounted within the casing or housing 1, is a substantially cylindrical or other designed casing 5, the bottom 6 thereof being foraminous. This cylindrical casing is adapted to receive a filtering material 7, which material may be of the usual or any preferred character. Secured to the inner wall of the casing or housing 1 and bent somewhat inwardly, is a supporting flange 8, while the lower edge of the casing 5 is provided with a downwardly and outwardly projecting flange 9 which is adapted to be seated on the supporting flange 8 to support the casing 5 in the main casing or housing 1. Arranged in the bottom of the supporting flange 8, is a packing 10 which makes a water-tight connection at such point and also affords a generally better construction than ordinarily.

A top 11 formed of foraminous material is provided for the cylindrical casing 5, said top being constructed as a perforated plate or screen, as desired and in order to secure said top 11 in place, locking lugs 12 are provided at the top of the casing 5, on the inner wall thereof. In order to permit the top 11 to be positioned, notches 13 are provided in the peripheral edge at diametrically opposite points thereon to permit said top to be disposed below said lugs and on top of the filtering material 7. In placing the top in

use, it is obvious that the notches 13 are positioned to register with the lugs 12 and said top is then given a partial rotation to dispose the notches out of registration with the lugs. A locking strip 14 is provided for introduction at its ends under the lugs 12 to bind tightly against the foraminous top 11 and this strip forms a diametrical locking member to retain said top in place. This strip is off-set at its center, as shown at 15 to form a handle member or the like, whereby the casing 5 with its contents may be lifted, when desired.

In order to retain the casing 5 with the 15 contents therein and top thereon in place in the main casing or housing 1, we provide the leaf springs 17. These leaf springs are secured at their upper ends to the inner wall of the casing or housing 1, adjacent its top 20 and the same are bent outwardly toward the lower free ends thereof. These lower free ends are engaged with the top of the casing 5 and obviously lock the latter in position in the casing 1. In order to remove the casing 25 5 from the casing 1, said springs 17 must be first forced outwardly against the walls of the casing 1, in order to release the engagement thereof with said member 5.

A plurality of perforated baffle plates 18 30 are provided adjacent the bottom of the main casing or housing 1, said plates being arranged in spaced relation and parallel to one another below the bottom of the casing 5 and suitably secured upon the horizontally 35 disposed flange of an annular member 18' which is of angular cross sectional form and has its vertical flange fixed to the wall of the casing 1. Each of the plates 18 is provided with a plurality of openings 18^a arranged in staggered relation, the openings in one plate being disposed out of registering relation with the openings in an adjacent plate. These plates are arranged in alignment with the inlet opening of the casing 40 or housing 1 and are adapted to retard the current of the water entering said casing 1 from the inlet pipe. By retarding the current in this manner, the same is caused to flow 45 evenly upward through the filtering casing 5 and all extraneous matter and substances, together with the sediment will be deflected and caused to settle on the bottom 2 of the main casing or housing 1. A discharge faucet 19 is provided in the wall of the casing 55 or housing 1, adjacent the lowermost portion of the bottom 2, to admit of the sediment being readily removed, when desired. It is to be observed that the plate nearest to the faucet 19 is spaced a considerable distance 60 from the next plate 18, the remainder of said baffle plates being equally spaced apart as clearly shown in Fig. 3. By providing this wide open space above the inclined catch basin 2, it will be appreciated that the plates 65 18 offer no impediment to the collection of

the sediment in the lower end of the basin so that it may be readily withdrawn therefrom when the faucet is opened.

This device is adapted for use in connection with large plants or on smaller scales, 70 such as domestic use. In either instance, twigs, branches, leaves and the like are adapted to flow with the water toward the filter and we have also provided a means for removing such substances prior to the entrance of the water to the filter proper. To this end, a rectangular housing 20 is provided, from the top and bottom of which project the tubular portions 21 and 22, respectively. The lower projecting tubular portion 22 is adapted to be received in the upper end of the inlet pipe 3 and the opening between the housing 20 and the lower tubular portion 22 is covered by a plurality of diagonally extending rods 23. This housing 20 is entirely closed, with the exception of the front wall thereof and a hinged door 24 is provided for the front wall which is formed of foraminous material, which is a perforated plate or screen, preferably the latter. Thus, as the water flows toward the inlet pipe 3, the twigs, leaves and the like will be received on the grading formed by the rods 23 and may be readily removed by the opening of the door 24.

We have provided a top for the entire device, indicated as 25. The same is provided, on its under face, adjacent its outer peripheral edge, with an angular and depending flange 26 and is designed to fit within the 100 wall of the casing or housing 1, at the upper end thereof. A handle member 27 is secured to the top 25, whereby the latter may be readily removed or placed in position, when desired.

While we have particularly described the elements best adapted to perform the functions set forth, it is obvious that various changes in form, proportion and in the minor details of construction may be resorted to without departing from the spirit or sacrificing any of the principles of the invention.

Having thus described our invention, what we claim is:—

1. In a filtering device, a main casing provided with inlet and outlet pipes, an annular inwardly inclined flange fixed to the inner wall of said casing adjacent the bottom thereof, an inner filtering casing provided upon its lower edge with an outwardly inclined downwardly-extending flange, a packing ring arranged between said first-named flange and the wall of the main casing upon which the flange of the filtering casing is adapted to seat, and means secured to the inner wall of said main casing adjacent its upper end to coöperate with said filtering casing and removably retain the same in position upon said packing ring.
2. In a filtering device, a main casing hav-

ing inlet and outlet pipes, an inner filtering casing, supporting means for said inner casing secured to the inner wall of said outer casing, a plurality of leaf springs secured to 5 the inner wall of said outer casing adjacent the upper end thereof and adapted to coöperate at their free ends with the upper edge of said inner casing to retain the latter in place within said outer casing.

10 In testimony whereof, we hereunto affix

our signature in the presence of two witnesses.
